UNITED STATES PATENT OFFICE.

GEORGE H. DERN, OF SALT LAKE CITY, AND THEODORE P. HOLT, OF PARK CITY, UTAH.

ORE-ROASTER.

1,113,962.

Specification of Letters Patent. Patented Oct. 20, 1914.

Application filed April 9, 1914. Serial No. 830,670.

To all whom it may concern:

Be it known that we, GEORGE H. DERN and THEODORE P. HOLT, citizens of the United States, residing, respectively, at Salt Lake City, county of Salt Lake, State of Utah, and Park City, county of Summit, State of Utah, have invented certain new and useful Improvements in Ore-Roasters, of which the following is a specification.

10 This invention relates to blast ore roasters.

Our object is the provision of a novel ore roaster adapted for carrying out the roasting process set forth in the application of Neils C. Christensen, Jr. and Theodore P. Holt, filed August 3, 1911, Serial No. 642,088 and that set forth in the patent to Wilhelm Buddeus No. 1079897, dated November 25, 1913; and still further, adapted for the performance of a blast roasting process embodying improvements on the roasting process of the said application and patent.

Our invention is adapted for the treatment of any metal bearing ore, particularly those ores which require an oxidizing or chloridizing roast preparatory to the extraction of the valuable metals by any suitable solvent.

The invention relates, more particularly to the provision of a novel blast roaster adapted for the treatment of ores which are first finely crushed and moistened and (if not carrying the necessary fuel themselves) are mixed with sufficient fuel to adapt them for roasting by internal combustion of the mass, by forcing a blast of air through the charge and for the treatment of the charge in a novel manner.

In the present invention we have provided a blast ore roaster embodying improvements and novel features by which loss by volatilization, which in other types of roasters when used for chloridizing roasting is from ten to fifteen per cent., is practically eliminated; a saving of about seventy-five per cent. of the fuel consumed by other roasters is effected; the cost of installation is greatly minimized; the fumes are controlled and, when desired, may be easily condensed; the roasted product is free from slime and consequently much easier to leach; and dusting, with its considerable loss, is entirely eliminated.

Our ore roaster is continuous in operation to the extent that the fire is never allowed to go out and the roaster is never completely emptied, although it is charged

and discharged intermittently; further, the roasting zone is allowed to travel upward until it reaches the top of the charge, or substantially so, whereupon it is dropped suddenly, after which it can again travel to the top.

A desideratum in roasting ore by our process is to obviate the occurrence of portions or sections of the charge which offer less resistance than the remaining portions thereof, because such weak places permit a rush of air through them and thus the ore roasts more rapidly at these points than in other portions of the charge. We have found that a continuous discharge of the roasted ore, as has been previously proposed, has invariably cracked the cake, or caused it to settle away from the walls of the roaster, thereby forming air channels. The present roaster is adapted to cause the charge to drop quickly and freely at desired intervals, and while cracks may occur, they may be sealed up with a layer of fresh ore and cause no difference in roasting.

The present roaster maintains a permanent but shifting roasting zone in the columnar charge of ore and removes the roasted ore from beneath the roasting zone at intervals, fresh unroasted ore being added on top as required.

Our invention consists, first, in the combination of an open charge-supporting, air distributing, crushing grate composed of spaced rotatable or rockable grate bars, a charge-holding or roasting chamber disposed thereabove and in which the charge is supported by said grate, and an equalizing air pressure box or chamber arranged below the grate and normally free from contained roasted ore, or substantially so, but also incidentally serving as a hopper for the temporary holding of such portion of the charge as is crushed and lowered by the grate, until the discharged roasted ore may be removed; second, a novel grate composed of rotatable or rockable grate bars, operated by suitable means to rock or rotate, according to the nature of the ore which is undergoing treatment. The grate bars are normally stationary, but when the charge is to be dropped, they are set in operation and the teeth or projections thereon disintegrate the bottom of the roasted cake and the entire ore mass is thereby quickly and evenly lowered without disturbing the relation of roasted ore particles to

each other, while the ore crushed from the ore cake is allowed to drop freely between the rolls and below. If the rolls are rotated slowly and continuously, as may be preferable with certain ores, we may feed the ore continuously into the roasting chamber and continuously take off the roasted ore from the air box and collector. The rolls are arranged with ample free spaces therebetween, which permits free passage of the crushed and roasted ore and insures a even distribution of the air blast. When the ore is of a nature which results only in slight caking during the roasting process, we find it preferable to rock the rolls or bars constituting the grate, because relatively rapid rotation, as distinguished from rocking, would disturb the roasting bed too much and cause uneven settlement and channels in ores of that character. With ores which cake thoroughly, we may rotate the grate rolls continuously instead of rocking them, and in that event, we preferably drive them in pairs, the members of which rotate in opposite directions. The provision of rotary rolls constituting the grate permits a wide range of adjustments as to speed and character of motion.

Our invention contemplates, further, the provision of improved means for sealing the cover of the roaster and preventing the escape of the gases which are annoying and harmful to operatives. To that end, we provide a trough-like seal in which a suitable sealing material, such as moist clay may be placed to coöperate with a flange on the cover and thereby effectively seal the roaster against escape of the gases which are thus compelled to enter the take-off flue.

Our invention consists, further, in the combination with the overhanging lower end of the charge-holding roasting chamber, of a grate composed of rockable or rotatable rolls whose ends are disposed beneath said overhanging lower ends of the roasting chamber thus preventing the ore from being caught between the ends of the rolls and the walls of the chamber.

We are aware that our invention may be carried out by other specific embodiments than those set forth hereinbefore and which are hereinafter referred to. The present embodiments of the invention are to be considered as illustrative, rather than restrictive, of the scope of the invention.

In the accompanying drawings: Figure 1 is a vertical section through the center of the roaster on the line 1-1, Fig. 2; Fig. 2, a cross section on the line 2-2, Fig. 1; Fig. 3, a vertical section on the line 3-3, Figs. 1 and 2; and Fig. 4, a detail showing a crank driving motion for the grate rolls.

The body 1 of the roaster is preferably square or rectangular in cross section, being provided with a suitable refractory lining 2

and with an air box or chamber 3 provided with a discharge gate 17. Supports 4, resting on a suitable foundation, sustain the weight of the roaster, with the discharge gate 17 in suitably raised position. 70

The cover 5 which is suitably hinged at 20, is provided with a refractory lining 6 and may be raised and lowered by a cable 7, which passes over a sheave or pulley to a suitable counterweight (not shown). At the 75 upper part of the roaster is a trough 10. The cover 5 carries a flange 10^a which, when the cover is down, enters the trough 10. Any suitable material, such as moist clay, is placed in the trough 10 and when the 80 flange 10^a is embedded therein, which occurs when the cover is down, there is thereby provided an effective seal against the escape of gas and smoke from the top of the roaster, such smoke and gases passing into the flue 9 85 which is provided with gate or damper 8 and leads to a suitable stack or to a condenser.

The grate is composed of crushing rolls 11 which are provided with numerous projections or teeth 11^a and are carried by shafts 11^b revolvably mounted in journal boxes 11^c on suitable removable air-tight closures 2^a extending the full width of the roaster and bolted thereto. The crushing rolls extend 90 across the roaster and have their ends disposed under the refractory lining 2 and are located above the air box 3. These rolls are preferably spaced a relatively great distance apart, Fig. 2, so that the crushed ore will 95 readily fall between the rolls into the air box 3 when said rolls are set in operation.

We do not limit ourselves to the precise form of rolls shown in the drawings, as we are aware that rolls of other design would 100 produce the same effect.

The sides of the roaster may have crushing abutments 2^b in the form of concave breasts which are disposed parallel to the outermost rolls, Fig. 3.

The rolls may be rotated or rocked by any suitable means. We have shown one such means in Figs. 1 and 2, whereby the rolls may be continuously rotated. In Fig. 4, we have shown a crank which may be used to 110 impart a rocking motion to the rolls.

The shafts 11^b are provided with pinions 12. A suitably mounted drive shaft 19, is provided with gears 13 meshing with the pinions 12 and it has a belt pulley 16 for 120 the application of power. Preferably, the gearing arrangement is such that pairs of the rolls 11 will be driven in opposite directions to each other.

With those ores which cake quite 125 thoroughly during roasting, it is preferable to continuously rotate the rolls, but only during the time when it is desired to disintegrate the cake and lower the charge. With those ores which do not cake tena-

ciously it is preferable to impart a rocking movement to the roll 11. In this case the crank 16, Fig. 4, may be substituted for the belt pulley 16 to rock said crank through an arc such as shown by dotted lines in Fig. 4. When this is done, the rolls rock back and forth. Ores which cake together only slightly during the roasting process would settle unevenly and provide air channels if the cake were disintegrated by continuously rotating rolls. It will be seen, therefore, that the provision of rolls permits of a wide range of adjustments according to the requirements of a large variety of ores. We are aware that other means may be provided for imparting either the rocking or the rotating motion to the rolls and we do not limit ourselves to the specific embodiments described.

20 Air is admitted to the box or chamber 3 below the grate by an air blast pipe 14 which is regulated by a valve 15.

In Fig. 3, 18 represents a sluicing launder to convey the roasted ore to leaching vats. 25 The gases from the roasting ore may be forced into flue 9 by the blast pipe 14, or a suction fan may be attached to the flue 9 to aid in carrying the gases away.

We consider it advisable to provide a 30 smooth interior for the refractory lining 2 and that it be of somewhat greater internal size toward its lower part where it approaches the grate, in order that an even settlement of the charge will occur. Finely 35 divided ore, properly moistened, cakes together in roasting, and by providing the foregoing features, the ore mass may be lowered without disturbing the roasting ore particles in their relation to each other, whereas if the internal size of the roaster 40 is the same from top to bottom or is smaller at the bottom, the charge is liable to "hang up" by adhering to the sides, thus necessitating hand work in relieving this condition. 45 The spacing apart of the rolls permits the material to drop freely from them and breakage is thereby prevented due to the crushing action which would otherwise take place. Furthermore, the spacing of 50 the rolls insures a free distribution of the air blast.

The air box 3 provides a free air-distributing chamber from which the air blast has access to all parts of the grate and through the latter to all parts of the charge. 55 The ends of the grate are overhung by the lower end 2^a of the lining 2. This prevents the ore from getting between the ends of the rolls 11 and the wall 2 and prevents 60 breakage.

The roast may be started in various ways, but the following has been found in practice to give the best results: The grate rolls 11 are first covered with a layer of roasted 65 ore lumps of such size that they will not

fall through. Three or four inches of fine ore is then spread over the said roasted ore lumps to insure an even distribution of the air. A layer of small pieces of wood to the depth of two or three inches is then placed on 70 the fine ore. Kerosene may be sprinkled over the wood. Upon igniting the wood a quick spreading of the flame over the entire surface occurs, the air blast being meanwhile regulated by the valve 15. After the wood 75 is burned to coals the first charge of suitably prepared ore is put on. The fuel in the ore becomes ignited and the mass begins to toast, the roasting zone proceeding upward. The cover 5, which has been thrown 80 back up to this time, is now closed, so that the smoke and gases pass out through the flue 9 to a condensing chamber or to a chimney. At intervals the cover is raised and additional charges of ore are added, 85 until the roaster is filled. The roasting zone meanwhile is ascending and finally approaches the top of the roaster, say, to a point about level with the bottom of the flue 9, whereupon the air blast is shut off 90 by closing the valve 15, and the charge is lowered. Up to the time of lowering the charge, the grate rolls 11 are allowed to remain stationary, but when the charge is to be lowered, power is applied to either 95 continuously rotate said rolls or to rock them, according to the nature of the ore being roasted. The teeth, projections, or points 11^a scratch or scrape and crush or cut off the bottom of the roasted cake and 100 the broken off portions of roasted ore fall through the spaces between the rolls and into the hopper 8. When desired, the gate 17 is opened to discharge the roasted ore into the sluicing launder 18, but the ore 105 may be discharged directly into a bin, car, or onto a conveyor. The charge having been lowered, as described, to the desired distance, and the ore let out of the box 3, the gate 17 is closed, the power cut off so that 110 the rolls 11 remain stationary, and a fresh charge of ore is delivered into the roaster, the cover 5 having been previously opened. The cover 5 is then closed and the valve 15 115 opened, and the roasting operation is resumed until the roasting zone, by its ascension finally reaches the desired point where it is advisable to again drop the charge.

In our roaster, the heated air and gases travel in an opposite direction to the ore 12 and it will be seen, therefore, that the roaster applies the principle of "counter currents" to the process of blast roasting in a most economical manner. It also secures an intimate contact between the active 12^a gases of the roast and the mineral particles of the ore so as to produce the desired reaction with a minimum of reagents. In the old types of roasting furnaces, the loss of 130 valuable metals by volatilization and dust-

- ing often exceeds ten per cent of the total value of the ore. We have demonstrated on a commercial scale that there is practically no loss of valuable metals when roasted in our roaster and that the gases are entirely free from dust, comparatively cool, and concentrated, and can easily be condensed for leaching purposes; further, that the roasted ore is practically free from slime and is brought to a porous character which is an ideal condition for subsequent leaching. Many ores are of such a slimy character that solution will not percolate through them. Our roaster changes their texture so that they can be leached which is cheaper than agitation, and flotation. We can condense the acid and chlorine from the gas coming from our roaster and utilize them in leaching solutions.
20. Where the situation demands that a chloridizing roast be prepared, additional reagents, such as salt, pyrite, etc., are added to the mixture before it is charged into the roaster.
25. In our roaster we provide means for carrying out the Christensen and Holt and Buddens roasting processes but, in addition, we carry out a new or improved roasting process by new means. The charge is supported by the grate in our invention, free from contact with any previously roasted ore below the grate. The grate is not embedded in ore above and below it as in the Christensen and Holt and Buddens processes. The provision of the air or wind box 3 which is never filled with ore, causes the blast to be equalized and also to be distributed to all parts of the grate, the latter being constantly subject to the blast, under whatever control of the latter may be exercised by valve 17. The box 3 also acts as a roasted ore collector but its latter function does not interfere with its service as an air or wind box and, in carrying out the process of roasting, we, therefore, not only progress the roasting zone upwardly, as in the Christensen and Holt and Buddens processes, but also, support the column of roasting ore while allowing the roasted and scraped off ore to freely drop or fall away from the grate and at the same time have a self-equalizing source of air blast.
- Having thus described our invention, what we claim as new and desire to secure by Letters Patent is:
40. 1. An ore roaster adapted for roasting a single columnar charge by internal combustion thereof, an upper roasting chamber for holding said charge, an air distributing

50. rotatable rolls collectively arranged and adapted for directly supporting a single columnar charge in said chamber and for crushing or disintegrating the ore when said rolls are rocked or rotated, to discharge the disintegrated ore through said grate, a combined collecting and air pressure chamber located below said grate, and means for introducing an air blast into said collecting and air pressure chamber and upwardly through said grate into a charge supported thereon for the purpose of roasting the charge solely by internal combustion thereof.

2. In an ore roaster adapted for roasting a single columnar charge by internal combustion thereof, an upper roasting chamber for holding said charge, an air distributing crushing grate comprising rockable or rotatable rolls which are provided with teeth, said rolls being separated from each other by free discharge spaces, and collectively arranged and adapted for directly supporting the single columnar charge in said chamber, and for crushing or disintegrating the ore when said rolls are rocked or rotated, to discharge the disintegrated ore through said grate, a closed collecting and air pressure chamber located below said grate, and means for regulating said air blast introducing an air blast into said collecting and air pressure chamber and upwardly through said grate into a charge supported thereon for the purpose of roasting the charge solely by internal combustion thereof.

3. An ore roaster having a charge holding roasting chamber in combination with a charge supporting grate having rockable or rotatable rolls with outer ends are overhanging by the lower part of the walls of said roasting chamber.

4. An ore roaster having a charge holding roasting chamber, in combination with a charge-supporting grate having rockable or rotatable rolls whose outer ends are overhanging by the lower part of the walls of said roasting chamber, and a closed air pressure and collecting chamber located below said grate.
